UNITED STATES PATENT OFFICE.

GILBERT S. WALKER, OF PITTSBURGH, PENNSYLVANIA.

AUTOMATIC WATER HEATER.

Original application filed January 31, 1917, Serial No. 145,602. Divided and this application filed September 15, 1922. Serial No. 588,506.

To all whom it may concern:

Be it known that I, GILBERT S. WALKER, a citizen of the United States, a resident of Pittsburgh, in the county of Allegheny and 5 State of Pennsylvania (whose post-office address is care of the American Society of Mechanical Engineers, 29 W. 39th Street, New York, N. Y.), have invented a new and useful Improvement in Automatic Water 10 Heaters, of which the following is a specification.

My invention relates to automatic water heaters, consisting in the combination, constructions and arrangements hereinafter described and claimed, (being a division of application 145,602 filed January 31, 1917).

The object of my invention is to provide a water heater whose automatic action is dependent upon the joint action of two 20 thermostats, with the intent of eliminating the piston water valve which has heretofore been used. Other objects and advantages will appear in the following specification, and the novel features of the invention will 25 be particularly pointed out in the appended claims.

My invention is illustrated in the accompanying drawings, forming part of this application, in which:

30 Fig. 1 is a horizontal section of the device (and is identical with Fig. 4 of application 145,602).

Fig. 2 is a vertical section through a portion of the device on the line 2—2 of Fig. 1.

35 Fig. 3 is a side elevation of the valve chamber, the diaphragm being removed.

Fig. 4 is a detail of the diaphragm.

Fig. 5 is a vertical section through the valve chamber.

40 Fig. 6 is a view of the valve chamber with the cover removed.

A heater casing 61 encloses a heating coil 62 heated by main burners 63. The top of the coil 62 is connected by a riser 62^a and return bend 62^b to the auxiliary thermostat A. The riser is flexible and the hole through the heater casing for rod 69 is large enough to permit the necessary movement of this end of the thermostat under 45 the influence of temperature changes. This thermostat is horizontally disposed and much of its length is within the heater casing. At its right hand end there is a downward connection CWI to the cold water 50 supply system of the house. The main

thermostat B is also horizontally disposed and its right hand end is in communication at HWO with the hot water pipe system of the house. At the free or left end of the main thermostat B there is a flexible pipe 60 71 passing through a large hole in the casting and communicating with the the bottom of the coil 62. The auxiliary thermostat A with the connections 62^a at one end and CWI at the other end, both extending downwardly, forms an inverted trap. The water that is warmed by the pilot or auxiliary burner P and which is therefore somewhat lighter, will be retained in this trap and in contact with the auxiliary thermostat instead of circulating away to other parts of the heater. Both thermostats are preferably of thin copper tubing. At the left or free end of the auxiliary thermostat A there is attached a block 68 into which is 75 screwed a rod 69 to transmit the movement of the thermostat to the auxiliary lever 75 within the valve casing or chamber 70. In like manner the main thermostat B has attached to its left or free end 71 a block to which a rod 72 is attached to transmit its movement to the main lever 82 within the valve chamber 70. The right or fixed ends of both thermostats are secured by the pipe frame 67 to the valve casing 70. The frame 70 is also the main gas pipe leading from the chamber 95 on the valve casing 70 to the main burners 63, the right hand end of this pipe being closed at 66 to prevent escape of gas. 80 85

The right hand end of the pilot pipe P' is attached to the end 66 of the thermostat frame, and its left end extends into the valve chamber 70 and is provided with a forked bearing f adapted to come into contact with the knife edge 76 under certain conditions explained further on. The fork is open so gas can pass from the chamber 70 to the pilot light P, air for combustion being drawn in through a mixer M. It will 90 95 be seen from Fig. 2 that the pilot burner P is disposed underneath the auxiliary thermostat A so as to heat it.

Referring now particularly to Fig. 5, it will be seen that a flexible diaphragm D is provided to allow free movement of the rods without leakage of gas. The rod 69 has a bearing 73 on a knife edge 74 of the auxiliary lever 75. The fulcrum of this lever is at 76 and the fulcrum bearing 77 100 105 110

is on a screw stud carried by the casing 70. The lever 75 extends downwardly and has at its lower end a knife edge 78. This presses against the upper contact point of an intermediate lever 79, the lower contact point of which is pressed by a knife edge 80 carried by the main lever 82.

Referring now particularly to Fig. 3 it will be seen that the main lever 82 has a knife edge 83 similar to the previously described lever, this knife edge 83 being engaged by the bearing 84 at the end of the rod 72 (see Fig. 6). It will be noted that the lever 82 fulcrums on the knife edge 85 resting against the bearing 86 attached by a screw stud to the wall of the casing. The lever 82 extends downwardly and has at its lower end a knife edge 80 pressing against the lower contact point of the intermediate lever 79. A regulating screw 81 is carried by the casing 70 and limits the movement of the lever 82. The centers of the contacts of the three bearings on lever 75, as well as the centers of the contacts of the three bearings on lever 82, are in a straight line, although the line is not parallel to the sides of the casing, and the body of the lever is bent to convenient shape.

The long arm of the intermediate lever 79 (see Figs. 5 and 6) extends horizontally to the left and the upper side of its left end presses against the bottom of a rocking knife edge 87, the upper edge of which presses against the under side of a horizontally disposed gas valve lever 88. One end of this lever 88 is pressed upon by an adjustable screw 89 and the opposite end presses against the bottom of a valve stem 90, which carries the main gas valve 91 at its upper end (see Fig. 5). The valve is urged away from its seat by a weight 91^a on the valve stem. This weight, acting through the system of levers just described, keeps a strong force on the thermostat tubes.

A gas inlet 92 (see Fig. 1), is connected to the city gas main and conducts gas through the gas cock 93 to the small chamber 93^a on the lever casing 70. The main valve 91 controls the flow of gas from the chamber 93^a to the lever chamber 70. A small bypass 93^b around this main gas valve is controlled by a cock 93^b and supplies the small amount of gas required by the pilot burner P.

On the top of the valve casing 70 is a delicately adjusted relief valve 94 which permits excess pressure of gas in the lever chamber to go into the chamber 95, the latter communicating by means of a coupling 96 (see Fig. 1) with the pipe 67 which forms the frame of the thermostats. From here the gas is conducted through the T 97, and thence by the pipe 98 to the gas ring 99 that supplies the burners 63.

Operation: The pilot light P burns continuously and keeps the auxiliary thermostat A lukewarm as long as no water is drawn to disturb the temperature conditions. The gas valve 91 is adjusted by the screw 89 until it is closed. If now, for any reason, the temperature of the auxiliary thermostat A becomes slightly less, there will be a slight movement of the levers opening the main gas valve slightly and supplying more gas to the pilot. But this will not increase the gas pressure in the lever chamber 70 enough to open the relief valve 94 that controls the passage to the main burners.

When water is drawn through the heater, the temperature of the auxiliary thermostat A will be lowered so much by the incoming cold water that the levers will move far enough to fully open the main gas valve 91. The consequent increase of gas pressure in the lever chamber 70 will first cause the pilot light to flash up into a big flame and will then lift the check valve 94, allowing gas to flow to the main burners where it will be ignited by the enlarged pilot flame and the coil will be heated. As the outflowing water becomes warmer the main thermostat B will expand. This will at first have no effect on the main gas valve because the lower bearing of the intermediate lever 79 has been held by the screw 81.

When however, the temperature of the outflowing hot water has reached the predetermined degree for which the regulating screw 81 has been set, the main lever 82 will lift the knife edge 80 off the screw 81 and move the intermediate lever 79 and the main valve 91 in the closing direction. Continued movement of these parts due to higher temperatures of the outflowing hot water, will close the main gas valve 91 partly or entirely and will regulate the supply of gas to suit the amount of water being drawn and insure its delivery at nearly uniform temperature.

In winter, when the inflowing water is cooler than in summer, the auxiliary thermostat will contract more when water is drawn, and the main thermostat will therefore have to expand more before it will shut off the gas, resulting in the delivery of hotter water in winter and cooler water in summer.

When the flow of water stops, the auxiliary thermostat A will be heated directly by the main burners for the short time they continue to burn; it will also be heated by local circulation of hot water up from the lower turn of the coil and by the pilot burner. As soon as this thermostat is warmed a few degrees, the main gas valve will be closed, and the pilot burner will supply sufficient heat to keep it closed.

If the pilot should go out, the contraction of the pipe P' will operate the auxiliary lever 75 and close the main gas valve.

I claim:

- 5 1. In a water heater, a gas burner, a gas valve, a water heating coil, thermostatic means through which the water passes to the intake of said coil for operating said gas valve in one direction, and independent 10 thermostatic means at the outlet of said coil for operating said valve in the opposite direction.
- 15 2. In a water heater, a gas burner, a gas valve, a water heating coil, a thermostat through which water passes to the intake of 15 said coil, means operated by said thermostat for operating the gas valve in one direction, a thermostat in the coil circuit at the outlet thereof, and means operated by said thermostat 20 for operating said valve in the opposite direction.
- 25 3. In a water heater, a gas burner, a gas valve, a water heating coil, thermostatic means at the intake of said coil for operating the gas valve in one direction, a gas burner in close proximity to said thermostat for heating the same, and an independent thermostat at the outlet of said coil for operating said valve in the opposite direction.
- 30 4. In an automatic water heater, the combination of a heating coil, a burner, a fuel supply for the burner, a thermostatic means adapted to regulate the fuel supply in accordance with the temperature of the outflowing hot water, and an auxiliary thermostatic means for automatically bringing the burner into action when cooled.
- 35 5. In an automatic water heater, the combination of a water heating coil, a burner for supplying heat thereto, a thermostat at the inlet to the coil, a burner for heating said thermostat, a thermostat at the outlet

of the coil, and means operated by both of said thermostats for controlling the supply of fuel to the first mentioned burner.

45

6. In a water heater, a water heating coil, a burner to heat the coil, a fuel supply for the burner, a main thermostat adapted shut off the fuel supply in response to heat, an auxiliary thermostat adapted to respond to 50 flow of cold water into the coil from the water supply and shut off the fuel supply when such flow ceases, each thermostat acting independently of the other thermostat.

7. In an automatic water heater, a main burner, a main thermostat, an auxiliary burner, and an auxiliary thermostat heated by the auxiliary burner, each thermostat being adapted to shut down the main burner in response to heat, the main thermostat being 60 responsive to the temperature of the water heated by the main burner.

8. In an automatic water heater, a coil conveying water, a main burner to heat the coil, a fuel supply for the main burner, a 65 main thermostat and an auxiliary thermostat each adapted to reduce the fuel supply in response to heat, and an auxiliary burner adapted to warm the auxiliary thermostat, this thermostat being also heated by 70 the main burner, the main thermostat being responsive to the heat of the water heated by the main burner.

9. In an automatic water heater, a main burner to heat the water, an auxiliary burner, a main thermostat controlling the main burner, and an auxiliary thermostat responding to the temperature of water heated by both of the burners to shut off the main burner when the flow of water stops.
